UNITED STATES PATENT OFFICE

BARTINE J. COADY, OF NORWOOD, PENNSYLVANIA

LAUNDRY APPARATUS

Application filed November 20, 1926. Serial No. 149,564.

This invention relates to laundry apparatus and has more especial relation to a machine of this character particularly and essentially adapted for commercial use. The 5 most acceptable method of cleaning appears to be to place the articles to be washed in a container, forcing the cleansing liquid or "suds" through the articles in the container, applying rinsing liquid, and finally rotating 10 the container with said articles therein for removing the rinsing liquid therefrom by centrifugal force.

The leading object of the present invention is to overcome previous disadvantageous 15 features by the provision of novel laundry apparatus in which loading of containers, immersion in the "suds", throwing off of rinsing liquid and unloading of containers constitutes a continuous operation with the 20 result that the laundry work is expedited, less workers are required, and the patrons of the laundry therefore may benefit by reduction in charges.

A further object of the present invention 25 is to provide a novel arrangement, combination and connection of parts for attaining the results sought by the leading object in which the entire washing operation of loading, washing, and unloading of laundry articles 30 may be preferably practiced in a single plane, or in other words upon one floor level of the establishment.

A further object resides in the provision 35 of an overhead track for the continuous travel thereon in one direction of suspended containers which travelling from a loading station, usually in series or groups, are first moved to a washing station; are then advanced to a liquid rinsing removing station; 40 and are finally returned to an unloading station.

Other and further objects of the present 45 invention reside in the provision of certain novel details of construction as will appear hereinafter.

The invention consists of the novel construction hereinafter described and finally claimed.

The nature, characteristic features and scope of the invention will be more fully understood from the following description taken in connection with the accompanying drawings forming part hereof, and in which: Fig. 1, is a view in plan of laundry apparatus embodying the invention.

Fig. 2, is a view in side elevation illustrating certain parts shown in Fig. 1.

Fig. 3, is a view in end elevation of the "suds" tub.

Fig. 4, is a fragmentary view in longitudinal section of the "suds" tub.

Fig. 5, is a view in section taken upon the line 5—5 of Fig. 4.

Fig. 6, is a view in end elevation, partly sectioned, of the track, carrier truck, and 65 carrier, the latter being in position for being rotated.

Fig. 7, is a view in side elevation of the upper part of Fig. 6.

Fig. 8, is a top or plan view of Fig. 7, with 70 parts broken away; and

Figs. 9 and 10 are views in perspective of ratchet means shown in Fig. 8, and which will be specifically referred to hereinafter.

For the purpose of illustrating my invention I have shown in the accompanying drawings one form thereof which is at present preferred by me, since the same has been found in practice to give satisfactory and reliable results, although it is to be understood that the various instrumentalities of which my invention consists can be variously arranged and organized and that my invention is not limited to the precise arrangement and organization of the instrumentalities as herein shown and described.

In the drawings there is disclosed, generally stated, in combination a loading station; an overhead track; a trolley and complementary truck for operating along said track;

a carrier supported by said truck; an immersion tank; a station for carrier rotation; and a station to which the carrier is returned, all of the above parts being preferably located upon a single floor. Taking up the above parts in sequential relation, the reference numeral 1 designates a loading station at which place the attendant in charge places in a container or containers 2 preferably a series or group of containers, articles to be washed. When a sufficient number of containers have been supplied with articles to be washed the carriers are caused to advance toward a "suds" tub 3. In this movement, which as shown in Fig. 1 is toward the right, the carriers may be moved along the overhead track 4 in any desired manner. Each carrier, as will hereinafter be described, is equipped with an electrical motor 8, current to which is supplied from wire 4 through trolley pole 5. The trucks and their carriers are moved toward a tank 3 for containing a cleansing solution. While the carriers are advancing toward and prior to introduction of "suds" to the tub 3, an attendant in charge opens the entrance gate of the tub (which gate will be hereinafter described in detail) to permit the entrance of the series or group of carriers. With the group of carriers assembled within tub 3 (the respective motors of each travelling truck of course having been stopped by the attendant in charge) the said attendant closes the entrance gate, and opens valve of supply pipe 7 for the filling of tub 3 with cleansing liquid or "suds". With the group of carriers, containing articles to be washed, arranged within tub 3, the operator at tub 3 now starts the motors 8 (one for each carrier) to vertically reciprocate the plunger 9 in each carrier 2. Thus, as the plunger 9 of each carrier is vertically reciprocated within a carrier, the "suds" are caused to enter and egress through the apertured walls of the container. When this reciprocating plunger operation is continued for a desired length of time the operator in charge withdraws the cleansing liquid from tub 3; and continues the operation with a rinsing liquid; opens the exit gate of the tub 3; and advances the group of carriers previously contained in tub 3. The group of carriers are again stopped by the operator in charge at what I term a "suds" withdrawing station 51 where the carrier plungers are elevated free of the carriers and the carriers rotated for the removal by centrifugal force of said "suds". The carriers are again as a group caused to travel along the overhead track to an unloading station 56. This advance of containers, from station to station, is continuous in a given direction and preferably in a single plane; that is, upon one floor level. Thus, it is apparent that the loading and unloading stations may be in charge of one attendant and

that the tub 3 and station 51 may be in the charge of another attendant thus expediting the washing operation materially. A description of the above described parts will now be given.

Overhead track

Preferably arranged in substantially elliptical form, as clearly illustrated in Fig. 1, are a pair of tracks 10. These tracks 10, as very clearly shown in Fig. 6, are formed of I-beams and are arranged in spaced relation. The tracks are continuous in continuity and are adapted to have tracked thereon a plurality of trucks which support the carriers 2. Since all the trucks and since all the carriers are of the same construction a description of one will suffice, and such description of truck and its complemental carrier will now be given.

Truck and its carrier

Each truck comprises a pair of spaced, horizontally arranged I-beams 11, see Fig. 8, each of which beams 11 is provided with rollers 12. These rollers 12 are flanged, as clearly shown in Fig. 6, and are adapted to track upon the tracks 10 and have for this purpose swivel relation as at 13. Mounted upon each of the trucks above described is the motor 8 previously referred to. This motor is provided with a drive shaft 14 connected as by sprocket chain 15 with shaft 16. Shaft 16 has mounted thereon a worm wheel 17 and also a bevelled gear 18 which in turn is in mesh with another bevelled gear 19 mounted upon shaft 20. Bevel gear 18 is turnable on shaft 16 and carries a ratchet B, operable in one direction by a pawl 35 carried by an arm 35' keyed to the shaft, see detail Fig. 10. Shaft 20 has fixed thereto a carrier 2, which is preferably of sheet metal and perforated as at 23. This carrier shaft 20 is provided at its bottom with a spherical member 24 and is provided at its top with spherical member 25. The spherical member 25 is arranged for rotation within a casing 26 carried by the spring supported platform 27, as carried by each I-beam 11. Worm 17 is in mesh with a worm wheel 28 turnably mounted on a shaft 30. The worm wheel carries a ratchet A adapted to be turned in one direction by a pawl 29 carried by an arm 35" keyed to the shaft, see detail Fig. 9. Shaft 30 is in turn provided with a pair of cranks 31 pivotally connected to rods 32 having vertical adjustment as at 33 with tubular members 34 pivotally connected to the plunger 9. During advance of a carrier the motor 8 does not function. However, when a carrier or a plurality thereof have been admitted to a tub 3 and the respective gates closed and the tub filled with suds and the motor 8 started it reciprocates plunger 9 in each carrier 2. This vertical reciprocation

of a number 9 is accomplished by means of the ratchet A, shown in Fig. 9. Thus, as the shaft 20 is rotated the pawl 29 which is fixed to shaft 30 cooperates with its ratchet wheel to maintain the movement of shaft 20 in the proper direction for reciprocating a plunger 9.

Suds tub

10 While a carrier or carriers are arranged within the tub 3 it is necessary that cleansing and rinsing liquid be introduced, which is accomplished through valve connection 7. It is also essential that when the carriers are about to be advanced for rotary movement that the cleansing liquid be removed, and for this purpose valved outlet pipes 37 are provided. At each end of the tub 3 there is provided a vertically movable gate, best seen 15 in Fig. 4, it being understood that the gate at each end of the tub is of duplicate construction so that it is merely necessary to describe one of these gates. The bottom 38 of the tub 3, and referring now more particularly to the exit end of the tank (although the entrance end of the tank is of similar construction) is provided with a flat, cross piece 39 provided with a facing 40 of rubber, canvas, or other suitable material 20 in order to prevent leakage of cleansing liquid when the gates are closed. Movable vertically in a downward direction is a gate 41 comprised of a piece of sheet metal which in cross section, as clearly shown in Fig. 4, is of inverted V-shaped configuration. The spaced faces of the gate are maintained apart by means of struts 42. The outer face of the gate is provided with a pair of spaced rack bars 43. These rack bars each have meshing 25 therewith at the lower ends thereof pinions 44 mounted upon a horizontal shaft 45. The shaft 45 in turn is connected with a drive shaft 46 by means of a sprocket chain 47. The shaft 46 is provided with a hand wheel 48 by which motion may be imparted to shaft 46, thereby imparting motion to sprocket chain 47 and shaft 45 including gear 44 to elevate or lower a gate of the tub 3. As clearly shown in Fig. 5, the side walls of the 30 tub 3 are provided with angle pieces 49 arranged between which and the V-shape gate are rubber, fibre or other packing members 50.

Station for centrifugal movement of carrier

55 After the articles in the carriers 2 have been washed at which time the plunger 9 is vertically reciprocated to thoroughly cause the cleansing liquid in tub 3 to commingle with the articles in the carriers, the valves of the pipes 37 are opened to permit egress of the cleansing liquid in tub 3. After the tub has been emptied the gates at each end of tub 3 are raised so that those carriers within the 60 tub 3 may be passed to the station 51 for ro-

70 tary movement and a new batch or group of carriers introduced to tub 3. Taking up now the description of the station for the rotary movement of the carriers, it is to be noted that a pair of spaced parallel members are provided upon the same level with the floor of tub 3, one member 52 being fixed, and the other member 52 being laterally movable by means of a hand screw 54. As the carriers 2 are advanced to the left in Fig. 2 the spherical member 24 of each carrier 2 is positioned opposite a set screw 54, as clearly shown in Fig. 6, whereupon the attendant in charge screws up the screw 54 so that the member 53 can be clamped with respect to fixed member 52 and the bearing 55 within which the spherical member 24 is contained. Thus, it is apparent that the upper and lower end of shaft 20 of each carrier while free to rotate are suspended or arranged against lateral or longitudinal movement. At this time the attendant in charge reverses the motor 8 by any convenient mechanism not shown in the drawings so that a carrier 2 is rotated, it being understood that the set screws of connections 33 are first loosened and the plunger 9 elevated free of a carrier 2, and the connections 33 thereafter secured to place with the plunger free of carrier 2. In order to secure rotation of vertical shaft 20 of each carrier 2 it is necessary to reverse the movement of each motor 8 and the ratchet B, shown in Fig. 10, is employed to effect the rotation of shaft 20. When the motor is reversed pawl 29 rides freely over ratchet A and the motion of plunger 9 is thus stopped. At the same time, pawl 35 which has heretofore been riding freely over ratchet B now actuates this ratchet to turn bevel pinion 18 by which shaft 20 and container 2 are rotated. As the carrier rotates the rinsing solution remaining in the articles being washed is deflected through the apertures 23 of a carrier so that no water remains in the articles in the carrier after sufficient rotation of the carriers.

Unloading station

The operator in charge now unloosens the screws 54, and advances the trucks and the carriers to the unloading end 56 of the platform, it being understood in this connection that it is convenient and economical to have the loading and unloading platform combined and in charge of a single attendant. During the movement of the carriers with the washed clothes therein towards the unloading end of the platform it will be understood that a new group or series of carriers are being introduced to the tub 3. Thus, at or about the time that the first group of carriers are being unloaded at platform 56, the attendant in charge of tub 3 has accumulated a new group or series of carriers, has closed the gates, and admitted washing liquid or suds to the tub. This operation is repeated and repeated in a

continuous and unbroken system, thereby providing a simple, economical, and efficient manner of washing clothes and the like.

What I claim is:

5 Apparatus of the character stated consisting of an overhead track for the travel there-over in a continuous direction of a clothes carrier which has a reciprocal plunger therein, a "suds" tub, a gate at each end of the tub operable to permit passage of said carrier, 10 valved means for supplying liquid to the tub, and means for operating the plunger while said carrier is in said tub.
